UNITED STATES PATENT OFFICE.

GEORGE B. KILLEEN, OF CHICAGO, ILLINOIS.

INVALID'S TOILET CHAIR.

Application filed November 12, 1926. Serial No. 148,082.

This invention has for its object to provide a roller chair for conveying hospital patients or invalids to and from the toilet without requiring a change of position after leaving the bed and until returning to the bed, the chair having an open seat and being adapted to be backed over the toilet, making it easy for the attendant and comfortable for the patient.

10 Another object is to provide such a chair so constructed that it will cause no injury to the patient in being backed over the toilet or removed therefrom and when the weight of the patient is on the footrest, as upon entering or leaving the chair, such weight will cause the chair to tilt lowering the footrest into engagement with the floor, where it will prevent the chair from rolling and so avoid accidents.

20 With the above and other objects in view, the invention consists in the invalid's toilet chair as herein claimed and all equivalents.

Referring to the accompanying drawings, in which like characters of reference indicate 25 the same parts in different views,

Fig. 1 is a perspective view of an invalid's toilet chair constructed in accordance with this invention;

Fig. 2 is a vertical sectional view thereof 30 in position over a toilet shown in dotted lines;

Fig. 3 is a plan view with the back sectioned showing the recess in the back of the seat to receive the toilet seat, and

Fig. 4 is a detail view showing the tilting 35 of the chair by weight on the footrest.

In these drawings, 10 indicates the chair frame consisting of front and back legs properly connected together to form a support for the seat member 11, the back of the chair frame being open and unobstructed to permit it to receive the opened toilet seat in the manner shown in Fig. 2 and preferably having arm rests 12 projecting therefrom.

40 The legs of the chair are provided with large casters 13 on the rollers of which it may be easily moved from place to place.

The back of the seat 11 is cut away or recessed at 14 to receive the toilet seat, as in 50 Fig. 2, and, to obtain the necessary strength, a steel brace 15 connects the back leg members and is suitably attached to the seat member to reinforce it. This brace is shaped to conform with the cut away back 55 of the seat.

The opening of the seat extends through

the front edge thereof and the deep cross-panel 16 connecting the front leg members is cut away or recessed at 17, as shown, and rigidly mounted thereon is a footrest 18 normally just above the level of the floor. The patient's weight on the footrest when entering or leaving the chair causes the chair to slightly incline, as shown in Fig. 4, so that the footrest bears on the floor and consequently the chair is prevented from rolling out. When the patient is seated on the chair, however, the chair may be readily moved from place to place and backed over the toilet, where it will receive the open toilet seat and cover in such a way as to not inconvenience the patient. The cut away opening 17 prevents any possibility of any part of the body of the patient being caught between the edge of bowl and the chair as 75 the latter is pushed over the bowl.

The chair is designed to afford the necessary strength for conveying patients or invalids in this manner with safety and comfort and with the least degree of disturbance 80 to the patient while making it easier for the nurse or attendant.

What I claim as new and desire to secure by Letters Patent is:

1. A roller chair for conveying hospital patients to and from the toilet comprising a chair mounted on rollers and having an open seat and an open back, the latter to receive the open seat and cover of a toilet when the chair is backed over the same. 90

2. A roller chair for conveying hospital patients to and from the toilet comprising a chair mounted on rollers and adapted to be backed over a toilet, said chair having a seat with an opening extending to the front 95 thereof and the front panel beneath the seat having a recess communicating with the opening of the seat.

3. A roller chair for conveying hospital patients to and from the toilet comprising a 100 chair mounted on rollers and capable of being backed over a toilet, said chair having a seat provided with an opening and having a footrest mounted thereon and normally positioned slightly above the level of the floor 105 whereby the weight of the patient thereon will cause the chair to tilt and the footrest to engage the floor to prevent the chair from rolling.

4. A roller chair for conveying hospital 110 patients to and from the toilet comprising a chair mounted on casters and having an open

back to receive the open toilet seat and cover when the chair is backed over a toilet, a metal brace extending across the back of the chair seat and secured thereto to reinforce it 5 and recessed to receive the toilet seat, said chair seat having an opening therein extending to the front and the front panel board beneath the chair seat having a recess

communicating with the opening in the chair seat, and a footrest mounted on the front panel board and normally positioned slightly above the floor but capable of engaging the floor under the weight of the patient to prevent the chair from rolling.

In testimony whereof, I affix my signature.
GEORGE B. KILLEN.
